UNITED STATES PATENT OFFICE

165,737

STEERING WHEEL

Robert E. Bourke, South Bend, Ind., assignor to
The Studebaker Corporation, South Bend, Ind.,
a corporation of Delaware

Application February 23, 1951, Serial No. 14,297

Term of patent 14 years

(Cl. D14—30)

To all whom it may concern:

Be it known that I, Robert E. Bourke, a citizen of the United States, residing at South Bend, in the county of Saint Joseph and State of Indiana, have invented a new, original, and ornamental Design for a Steering Wheel, of which the following is a specification, reference being had to the accompanying drawings, forming a part thereof.

In the drawings:

Figure 1 is a plan view of a steering wheel showing my new design;

Figure 2 is an elevational view of the steering wheel of Figure 1, as it appears looking upwardly from the lower end of Figure 1;

Figure 3 is an elevational view of the steering wheel of Figure 1, as it appears looking downwardly from the upper end of Figure 1;

Figure 4 is a side elevational view of the steering wheel of Figure 1; and

Figure 5 is a vertical sectional view taken centrally of the steering wheel of Figure 1, along the line 5—5.

I claim:

The ornamental design for a steering wheel, as shown.

ROBERT E. BOURKE.
